UNITED STATES PATENT OFFICE.

JAMES H. BRUMFIELD, OF ARMOR, WEST VIRGINIA, ASSIGNOR OF ONE-HALF TO
ELMER C. FERRELL, OF ARMOR, WEST VIRGINIA.

RAIL-SPIKE.

1,342,661.

Specification of Letters Patent.

Patented June 8, 1920.

Application filed April 26, 1919. Serial No. 292,779.

To all whom it may concern:

Be it known that I, JAMES H. BRUMFIELD, a citizen of the United States, residing at Armor, in the county of Mingo and State 5 of West Virginia, have invented a new and useful Rail-Spike, of which the following is a specification.

This invention relates to rail-spikes and has as its particular object to provide a 10 spike which when driven in the rail tie to hold the rail, will not work loose, due to vibration.

A second object of the present invention is to provide a railway spike which is positively 15 locked against movement and which does not necessitate the altering of the construction of the rail.

Another object of the invention is to provide a railway spike, which is as simple 20 to be assembled with the rails as the ordinary spike.

A further object resides in the provision of a railway spike which is simple in construction, consists of few parts, and which 25 may be manufactured and put in use at a minimum cost.

The above and other objects of the invention will become apparent from the following description and amplified therein, the 30 inventive features being defined in the appended claims.

With the above objects in mind, the invention consists of combinations of elements, arrangement of parts, and general assembly 35 which will be hereinafter referred to and illustrated in the accompanying drawing wherein:

Figure 1 is a view of a rail held in place by my improved spike, remote spikes being 40 also shown in position before being driven in the tie;

Fig. 2 is a side elevation of the spike;

Fig. 3 is a sectional view showing a modified construction of spike.

Referring to the drawing, the numeral 45 5 designates the shank of my improved spike which is tapered and otherwise formed in a conventional manner. The upper end of the shank is formed with a head 6 which 50 overhangs the shank.

Formed in the upper end of the shank is a transverse recess 7 which extends the en-

tire width of the shank and is overhung by the head 6.

A locking plate 8 is provided upon which 55 the rail 9 rests and is provided with rectangular openings 10 through which the spikes extend, four of these spikes being used in this instance to secure the rail to the ties. The metal is bent upwardly when the 60 opening 10 is struck to provide a locking tongue 11 which is normally angularly disposed at one side of the opening before the spike is driven into the tie. When the spike is driven into the tie the overhanging head 65 6 strikes the upturned tongue and forces the same into the recess 7. The spike is then driven until the head strikes the base flange of the rail with the tongue extending upwardly at an angle in position to prevent 70 displacement of the spike with respect to the rail.

In Fig. 3 a modified form of the spike is illustrated. In this modification the inner face of the shank just beneath the head is 75 provided with a notch 12 which receives the base flange of the rail and the outer and opposite face is formed with a rounded enlargement which increases the strength of the upper part of the spike, this part receiving the strain of the rail.

From the above it will be seen that the spike will be held against vibration as the train passes over the rail and thereby prevent the rail from becoming loose. 85

This disclosure is merely for the purpose of illustrating my idea and it will be understood that the construction outlined may be modified and that my limits of modification are only governed by what is claimed. 90

What is claimed is:—

1. The combination with a railway spike having a transverse recess therein, of a locking plate having an opening therein for receiving the spike, a bendable tongue disposed at one side of the opening adapted to be engaged by the head of the spike to force the tongue into the recess, said tongue extending upwardly and inwardly into the recess. 95

2. A rail spike including a shank having a head, the shank being provided with a transverse recess in close proximity to the head and extending the entire width of the 100

shank, a locking plate having a tongue struck therefrom and disposed upwardly at an angle and in the direction of the spike adapted to be engaged by the head of the 5 bolt to force the tongue into interlocking engagement in the recess when the spike is driven into the tie.

In testimony that I claim the foregoing as my own I have hereto affixed my signature in the presence of two witnesses.

JAMES H. BRUMFIELD.
